UNITED STATES PATENT OFFICE.

HARRY W. JONES, OF NEW YORK, N. Y., ASSIGNOR TO AMERICAN CAN COMPANY, OF NEW YORK, N. Y., A CORPORATION OF NEW JERSEY.

DESIGN FOR A SIFTER-TOP.

57,134.

Specification for Design.

Patented Feb. 22, 1921.

Application filed June 12, 1920. Serial No. 388,644. Term of patent 14 years.

To all whom it may concern:

Be it known that I, HARRY W. JONES, a citizen of the United States, residing at New York, in the county of New York and State of New York, have invented a new, original, and ornamental Design for a Sifter-Top, of which the following is a specification, reference being had to the accompanying drawing, forming a part thereof.

On the drawing:

The figure is a perspective view showing

my new design, being a top for dredging cans, powder cans and the like.

I claim:

The ornamental design for a sifter top, as shown.

HARRY W. JONES.
